UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

FOLDING-MACHINE.

1,152,259.

Specification of Letters Patent. Patented Aug. 31, 1915.

Application filed June 5, 1914. Serial No. 843,151.

To all whom it may concern:

Be it known that I, WILLIAM R. ALLEN, a citizen of the United States, residing at Cleveland, in the county of Cuyahoga and State of Ohio, have invented a certain new and useful Improvement in Folding Machines, of which the following is a full, clear, and exact description, reference being had to the accompanying drawings.

10 This invention relates to folding machines of the general type shown, described and claimed in Patent No. 839,313 granted December 25th, 1906 as the invention of Messrs. Nind and Julyan.

15 The object of the present invention is to produce a simple and cheap machine of that character, adapted primarily for folding small pieces of paper with one or more transverse folds.

20 The machine made in accordance with this invention is particularly well adapted to folding bills, statements, commercial note-size stationery, etc.

25 The machine is hereinafter more fully explained and its essential characteristics are summarized in the claims.

In the drawings, Figure 1 is a vertical section of my folding machine; Fig. 2 is a plan thereof; Fig. 3 is a fragmentary front 30 elevation of the portion of the machine associated with the stacker; Figs. 4 and 5 are end views of the machine,—Fig. 5 looking in the same direction as Fig. 1 and Fig. 4 in the opposite direction; Fig. 6 is a fragmentary view of the same end of the machine as shown in Fig. 4, in which is shown a portion of the folding mechanism in position to be operated by the cam, that is with the telescoping bar in its up position.

40 The frame of the machine shown consists of two upright end plates 10 and 11 connected by cross members 12 and 14, near the upper end of the side plates, mounted between them, and suitably secured to them, as, for example, by the screws 13 and 15.

45 The cross member 12 is substantially horizontal while the member 14 is inclined and the two parts constitute a table or support adapted to bend the paper intermediately.

50 The inclined portion 14 is adjustable about the pivot screws 13 (being locked by the clamp screw 16) to change slightly the pres-

entation of the paper at its convex bend to the dislodging roller hereinafter described.

The block of paper is shown at A in Fig. 55 1. It rests on the table 12 between suitable end guides 20 and 21 and side guides 23, 24, 25 and 26. The table is made of skeleton form shown in Fig. 2 for purposes of lightness. This skeleton form provides recesses 60 27 and 28 which form guides for the end blocks 20 and 21, these blocks having shoulders on their under side, whereby they are guided in the recesses and being clamped in adjusted position by suitable means, as, 65 for example, the screws 29 which pass through slots in the blocks into cross bars extending beneath the plate.

The side guides are shown as mounted on rods 30 and 31 extending between the side 70 plates of the frame. The side guides have downward lugs 34, Fig. 1, occupying transverse recesses 35 in the table and have bosses 37 which slidably embrace the rods 30, 31 and may be clamped thereto by set 75 screws 38.

By utilizing the members 12 as a part of the frame and also as the table for carrying the paper, I simplify and cheapen the construction. The side and end guides are 80 easily adjusted on the table to take any range of paper within the capacity of the machine.

The block of paper A rests on the table described between the side and end guides 85 and thus has a convex bent portion directly over the folding machine to be described. Above this bent portion is a surmounting weight 40. This weight consists of a cylindrical cross bar having a pair of parallel bars 90 42 extending in opposite directions parallel with the planes of the table. At the ends of the bar 40 are reduced extensions 43 which extend into vertical notches 44 in the end frames. The weight is therefore suitably guided in position but is free to rest on the paper and move downwardly with it.

The mechanism which gives the paper its first transverse fold consists of a stationary roller 50 (Fig. 1) and a coöperating roller 100 51 which is mounted to swing about the axis of the roller 50 and toward the paper (as illustrated by the broken lines 51^a in Fig. 1) and thus pinch the bottommost sheet and

dislodge it by drawing it between the rollers 50 and 51. This feature is shown and claimed in the prior patent to Nind and Julyan heretofore referred to.

As shown herein, the rollers 50 and 51 are rotated and the roller 51 caused to swing about the axis of the roller 50 by the following mechanism; that is to say,—journaled in the upright plates 10 and 11 is a driving shaft 60 on which is a gear 61 meshing with a pinion 62 on the shaft of the roller 50. This pinion meshes with a gear 63 on the shaft 65 of the roller 51. The pitch circles of the gears 62 and 63 are the same as the circumference of the rollers 50 and 51. The shaft 65 of the roller 51 is mounted in arms 66 which are journaled on the shaft of the roller 50, and these arms are suitably connected by a cross yoke 68. To swing the roller 51 upwardly to engage and dislodge the sheet, I extend one of the arms 66 downwardly and provide it with a roller 70 (Fig. 5) which projects through a slot 72 in the frame plate 10 and is adapted to be engaged by a cam 71 on the end of the main shaft 60.

Any suitable mechanism is provided for rotating the shaft 60, as, for example, the hand wheel 73 having a handle 74. The rotation of this shaft not only rotates the rollers 50 and 51, but causes the latter to swing upwardly against the paper, so that the bottommost sheet is pinched and fed downwardly between the rollers and thus intermittently folded.

In the downward feed of the folded sheet, the yoke bar 68 forms a guide for its travel. For some classes of stationery a single fold preferably in the middle of the sheet is sufficient. In other classes it is desirable to make two folds, for example, each approximately a third way from an end. My machine provides mechanism for taking the once folded sheet which passes downwardly along the guide 68 and either delivering it directly or giving it a subsequent fold, as will now be described.

Below the guiding yoke 68 are three rollers designated 75, 76 and 77, Fig. 1. These rollers are all geared together by suitable gears, as indicated at 78. The roller 75 has its shaft mounted in arms 80 which are pivoted on the inner face of the frame members 10 and 11. Suitable springs 81 connected to the frame members and to these arms tend to swing the roller 75 toward the roller 76. The amount of such swing is limited by the set screws 82. The roller 76 may conveniently be of metal and its coating roller 77 of rubber mounted on a suitable shaft. Each of the axes of these two rollers are stationary.

85 indicates a combined guide and knife. This consists of a cross member carried by ears at its ends on a rock shaft 86 mounted in the frame and having at its upper end a

rib 89 concaved above and below, thus coming to an edge opposite the contact line of the rollers 76 and 77. A suitable spring plate 90 is pivotally carried by a cross member 87 loosely mounted on the rock shaft 86 70 and lies along the front of the knife frame 85.

When it is desired to feed the once folded sheet out of the machine without a subsequent fold, the knife member 85 has the 75 position shown in Fig. 1, and the folded sheet, traveling down the right hand side of the yoke 68, passes between the rollers 75 and 76 and is then deflected by the upper concavity of the rib 89 and thus passes between the rollers 76 and 77 and beneath the stationary guard 93. Below this guard is a tooth stacker wheel 94 rotating in the opposite direction to the roller 77, and the teeth of this wheel coöperate with that roller 85 to feed downwardly the sheet onto the stacker table 100.

When the sheets are delivered, as shown at A¹ in Fig. 1, they rest on a notched portion 101 of the stacker table and are fed to 90 the left against a suitable stop block 103 by a packing arm 105. This arm is rigid on the rock shaft 106 which is oscillated by reason of a rock arm 107 (Fig. 5) connected by a pitman 108 with a crank pin 109 on 95 the cam 71. A suitable slot 110 in the pitman allows loose play and enables the packer arm to be given the desired movement. As the successive folded sheets are delivered, the block 103 slides along the smooth supporting arm 112 of the stacker frame, as will be well understood.

During the operation of stacking without subsequent folding, as just described, the set screws 82 are so adjusted that the roller 105 75 contacts with the roller 76 so as to cause the actual feeding of the paper. When, however, it is desired to give a subsequent fold to the once folded sheet, the screws 82 are turned inward to carry the roller 75 slightly 110 away from the roller 76, so that it does not cause an actual feed, but simply assists the downward movement of the sheet. The rock shaft 86 on which the knife frame 85 is mounted is, in this case, connected with a 115 suitable cam to rock the arm and thereby swing the upper end backward away from the rollers 76 and 77 so as to allow the once folded sheet to pass downwardly at the left of the arm until its lower edge strikes 120 and rests upon the portion 113 of the stacker frame. Then the knife swings to the left and the blade tucks the sheet between the rolls 76 and 77 so that it is given a subsequent fold. Then it is stacked as a 125 three panel fold, as shown in Fig. 1.

The mechanism which gives the desired swing to the rock shaft 86 is best shown in Fig. 4 and consists of an arm 120 rigid on that shaft and a sliding bar 121 telescop- 130

ing with the arm and clamped by a set screw 123, this bar coating with a cam 124 on the end of the main shaft 60. A suitable spring 125 connects with an arm 126 projecting from the arm 120 and tends to swing the knife arm 85 toward the left in Fig. 1.

128 indicates a stop for engaging the lower end of the telescoping bar when in its down position to hold the knife arm 85 stationary when this knife bar is not being used to give the three panel fold. In this down position the upper end of the bar is below the path of the cam 124. Accordingly, the knife bar remains stationary adjacent the roller 77 but preferably not in contact therewith. The cam 124 is conveniently formed on the side of the gear 61, which, as heretofore explained, meshes with the pinion 62. This gear also meshes with a pinion 132 on the roller 76. 129 indicates a pin carried by the pivoted frame member 87, and engaging a pin projecting outwardly from the side frame member 11. 25 This provides a suitable stop holding the spring fingers 90 normally in their vertical position, shown in Fig. 1, but allowing them to be readily swung rearwardly when desired.

30 The stacker table 112 above referred to consists of a cross bar 140 having the forwardly projecting arms 112 for holding the folded sheets and the rearward upwardly offset portion 113 for receiving the sheets to be folded. This stacker frame is conveniently adjusted by sliding up and down in ways on the inner side of the frame plates and being clamped by suitable thumb bolts 142. As the portion of the sheet to be 40 given a second fold which should stand beneath the point of the rib 89 is substantially the same as the width of the panel of the folded sheets beneath the stacker wheel, it is convenient to make the portions 113 and 45 the rest of the stacker table rigid so that one adjustment provides for both the stopping of the sheets to be given the second fold and for the receiving of the folded sheets.

50 It will be seen that my folding machine is extremely simple in construction, that it may be made very durable and with nothing whatever about it to get out of order. In the operation, the paper is simply placed 55 in a pile on the top of the machine, the side and edge guides adjusted approximately to the size of the sheet and the weight laid on top of the sheet. The telescoping extension of the knife arm is adjusted in or out, according to whether the sheet is to be given one or two folds. The roller 75 is set correspondingly and the stacker frame is adjusted according to the size of the folded sheets. Then it is simply necessary to rotate the hand wheel to

fold the paper lying on the table. The operation may be continuous as the weight may be removed and additional paper supplied without stopping the folding operation.

Having thus described my invention, what I claim is:

1. The combination, with a paper table, of folding rolls beneath it, a rod beneath the table, a side guide mounted to slide on the table and having a downward extension loosely surrounding said rod, and means for clamping the downward extension on the rod.

2. The combination, with a pair of upright side members, of an approximately horizontal top member secured to the side members and making a frame therewith, said top member constituting a paper table and having one portion at an angle to said horizontal portion to make a downwardly convex bend in the paper, folding rolls beneath an opening in said table, and means for changing the angle of one portion of the table top to adjust the presentation of the convex bend to the folding rolls.

3. The combination of a pair of upright side plates, a cross plate constituting a portion of the frame and a paper table, folding rollers beneath an opening in the cross plate, said side plates having ears extending above the cross plate and provided with notches, and a weight adapted to rest on a block of paper on the table, said weight being slidably guided by said notches.

4. The combination, with a paper table, a pair of folding rolls beneath the same, a second pair of folding rolls beneath the pair first mentioned; a pivoted blade carrying near its upper end a rigid rib with a concaved upper surface, said surface being adapted to form a guide for the sheet driven end foremost between the second pair of rolls, and means for swinging said blade to cause it to tuck the sheet intermediately between said second pair of rolls.

5. The combination of a pair of folding rolls, a knife adapted to tuck the sheets between said pair, a deflector carried by said knife for directing the sheets directly to the pair, an extra roll coating with the one member of the pair, a spring tending to force it against said member, and means for preventing it contacting when desired, whereby it is possible to positively feed the paper or 120 to simply guide it.

6. The combination, with a pair of folding rolls, of a second pair of rolls adapted to receive the folded product of the first pair, a combined deflector and tucking blade 125 adapted to coöperate with the second pair to direct the sheet end foremost to the same or to tuck it intermediately between them, a rock arm connected with the tucking blade, and a cam for operating said arm, said arm 130

having an adjustable extension to engage or miss said cam.

7. The combination, with a pair of folding rolls, of a second pair of rolls adapted to receive the folded product of the first pair, a combined deflector and tucking blade adapted to coöperate with the second pair to direct the sheet end foremost to the same or to tuck it intermediately between them, 10 a rock arm connected with the tucking blade, a cam for operating said arm, an extra roll coacting with the upper roll of the second pair, and means for adjusting said roll toward or from the upper roll of the second 15 pair and limiting the approach thereof.

8. In a folding machine, the combination, with a paper table, of dislodging and folding rolls adjacent thereto, delivering rolls, a stacker wheel coacting with one of the delivery rolls, a stacker table adapted to receive the folded sheet beneath the stacker wheel, said stacker table comprising arms rigid on a cross bar, said cross bar being guided in vertical ways on the inner sides of

the frame and adjustable up and down, and 25 clamping screws engaging the ends of the cross bar and the frame.

9. In a folding machine, the combination, with a paper table, of dislodging and folding rolls adjacent thereto, delivering rolls 30 adapted to act on a sheet folded by the rolls first mentioned, a stacker table adapted to receive the folded sheet, said stacker table comprising arms on a cross bar, said cross bar being guided in vertical ways on the 35 frame and adjustable up and down, extensions on the stacker table higher than the table and projecting beneath the second pair of rolls, and a tucking blade adapted to act on a vertical sheet resting on its lower edge 40 on said extension.

In testimony whereof, I hereunto affix my signature in the presence of two witnesses.

WILLIAM R. ALLEN.
